CASKET

John E. Corrigan, Ozone Park, N. Y.

Application September 20, 1935, Serial No. 41,401

1 Claim. (Cl. 27—12)

My invention relates to a new and improved casket.

One of the objects of my invention is to provide a casket having an improved type of adjustable support, for supporting the body, so that the body can be supported at any desired level, and in any tilted position relative to, the bottom of the casket.

Another object of my invention is to provide simple and efficient means for adjusting the height and the angle of the support, so that the device can be manufactured at low cost, and the operating parts are concealed.

Other objects of my invention will be set forth in the following description and drawing, which illustrates preferred embodiments thereof, it being understood that the above general statement of the objects of my invention is intended generally to explain the same, without limiting it in any manner.

Fig. 1 is a vertical sectional view of the improved casket, said view being partially in elevation.

Fig. 2 is a horizontal sectional view, the representation of the support having been eliminated in this view, in order to illustrate the remaining parts more clearly.

Fig. 3 is a sectional view on the line 3—3 of Fig. 2, the lower ends of struts 10a being broken away.

Fig. 4 is a top plan view, which illustrates a modification of the invention.

Fig. 5 is a sectional view on the line 5—5 of Fig. 1.

Referring to Figs. 1—3 inclusive, these show a casket 1, having a bottom member to which racks 7 are connected, by means of fastening devices 8. These racks are provided with ratchet teeth, as clearly shown in Fig. 1.

The body-support 2 is made of any suitable material.

Adjacent one end thereof, a bar 5, made of metal or any other suitable material, is connected to the underside of the support 2. A U-shaped frame 3, having a bottom member 6, is pivotally connected to the bar or bracket 5, by means of pivot pins 4. The lower member 6 of the frame 3 is shaped as shown in Fig. 1, and this lower member 6 can fit into the space between any pair of the ratchet teeth of the rack 7, so that said frame 3 provides a pivoted support, for adjustably holding the adjacent end of the support 2, at any desired height above the bottom of the casket.

Adjacent the other end thereof, a bar or bracket 9 is connected to the underside of the

support 2. As shown in Fig. 2, the said bracket 9 comprises two portions of unequal width, the portion which is of greater width being adjacent the right-hand end of the support 2. Hence each end-face of the bracket comprises an outer end-face portion and an inner end-face portion, the outer end-face portions being aligned, and the inner end-face portions being aligned.

A pair of struts or arms 10 are connected to the said bracket 9, by means of pivot pins 11a, 10 so that said struts are operatively connected to the support 2. The arms 10 are connected to a slide 14, by means of fastening devices 12. The members 12 are pivot pins, so that the arms 10 can turn relative to the slide 14. The slide 14 is 15 slidably mounted upon the tops of tracks T, which are suitably fastened to the bottom of the casket. Hence the slide 14 is slidably supported on the bottom of the casket.

The slide 14 has an angular cross-section, and a screw 17, having a threaded portion 17a, passes through an opening in the upstanding wall of the slide 14, and said threaded portion 17a of the screw 17 also passes through the internally threaded bore of a nut member 15, which is rigidly secured to the slide 14.

The screw 17 also passes through a U-shaped frame 16, whose bottom ends are suitably connected to the bottom of the casket.

A second pair of arms 10a are connected to the bracket 9, by means of pivot pins 11. Said pivot pins 11 are spaced longitudinally relative to pivot pins 11a, so that struts 10 cross the struts 10a. Said arms 10a are pivotally connected, by means of pins 18, to a cross member 19. The cross member 19 has an angular cross-section, and the screw 17 passes through an opening in the upstanding wall of said cross-member 19. The cross-member 19 is fastened to the bottom of the casket, by means of fastening devices 25. Hence the 40 lower ends of struts 10 are, in effect, pivotally connected to the bottom of the casket. Directly adjacent the rear surface of the upstanding wall of the cross-member 19, a collar 20 is connected to the adjacent smooth portion of the screw 17, 45 by means of a set screw or the like. The screw 17 also passes through a gasket 22, which is made of any suitable metal such as steel, and said screw 17 also passes through a gasket R, which is made of rubber or of any other suitable resilient 50 material. The right hand end of the screw 17 is provided with a recess 24, which has a non-circular cross-section, such as a square cross-section. A crank 23 is provided with an end which may be fitted into the recess 24, in order to turn 55

the screw 17. Due to the stepped shape of the end faces of the bracket 9, which is shown in Fig. 2, the arms 10 are outer arms, which are laterally spaced from the inner arms 10a.

5 The adjustment of the support 2 is as follows:—

One end of the support 2 is adjusted, by regulating the angle between the member 3 and the said support 2. This can be done by means of the openings 2a which are provided in the support 2, so that the operator can insert his hands through said openings 2a, in order to regulate the angle between the member 3 and said support 2.

Upon turning the crank handle 23, the turning of the screw 17 causes the longitudinal shifting and adjustment of the slide 14, along the tracks T. Since the cross-member 19 is fixed to the bottom of the casket, the longitudinal shifting of the slide 14 causes a change in the angle between the arms 10 and 10a, and the said support 2, so that 15 the right hand end of the support 2 is raised or lowered.

20 This construction makes it possible to mount the support 2 at any desired angle to the bottom of the casket, and to hold said support 2 in said adjusted position. The thread of the screw 17 is sufficiently fine, so that the slide 14 is held automatically in its adjusted position.

25 The member 16 serves as a supplemental support for the member 2, because if the right hand end of the support 2 is lowered sufficiently, the bar or bracket 9 will rest upon the top of the U-shaped member 16.

30 The embodiment shown in Fig. 4 and Fig. 5 represents a modification of the left-hand side of Fig. 1. In this modification, the underside of the support 2 has arms 30 pivotally connected thereto, by means of pivot pins 31. Each of these arms 30 has a tension spring S connected thereto, and said tension springs have their inner ends 35 fastened to the underside of the support 2, by means of pins 33. The tension springs S turn the arms 30, until their pawl ends engage the ratchet teeth of vertical ratchets 34, which may be cast integral with supporting legs 35, which are suitably 40 connected to the bottom of the casket. The upper ends of said racks 34 may also be connected 45

to the side walls of the casket, by means of fastening members 40. The openings 2a make it possible to manipulate the arms 30, so as to regulate the height of the adjacent end of the support 2, relative to the bottom of the casket.

5 The support 2 substantially conceals the operating parts, since the openings 2a are small.

I do not wish to be limited to the specific adjusting devices illustrated herein, or any of them, although the specific constructions which have 10 been illustrated represent the most desirable form of the invention. However, numerous changes and omissions can be made without departing from the spirit of the invention.

15 It will be noted that the adjusting means which are shown at the right-hand side of Fig. 1 are operated from the exterior of the casket.

The screw 17 is provided with suitable bearings in the openings of the upstanding flanges of members 14 and 19, so that the screw can turn 20 freely. The gaskets 22 and R may be suitably secured to the end-wall of the casket. The gasket R acts as liquid-tight and gas-tight packing.

25 I have shown preferred embodiments of my invention but it is clear that numerous changes and omissions can be made without departing from its spirit.

I claim:

A casket having a vertically movable support therein, a bracket connected to the underside of 30 said support, said bracket having stepped end-faces so that each of said end-faces comprises outer and inner end-face portions, the outer-end-face portions being respectively aligned and the inner end-face portions being respectively 35 aligned, a first pair of struts pivotally connected at their upper ends to said outer end-face portions and pivotally connected at their lower ends to a member which is slidably supported on the bottom of the casket for longitudinal to-and-fro 40 movement, a second pair of struts pivotally connected at their upper ends to said inner end-face portions and pivotally connected at their lower ends to the bottom of the casket, and mechanism 45 for actuating said member.

JOHN E. CORRIGAN.
